CLAIM

The ornamental design for a solar post light, as shown and described.

DESCRIPTION

FIG. 1 is a top, front and right perspective view of a solar post light showing my new design;
FIG. 2 is a front elevational view thereof, the rear elevational view being identical thereto;
FIG. 3 is a left side elevational view thereof, the right side elevational view being identical thereto;
FIG. 4 is a top plan view thereof; and,
FIG. 5 is a bottom plan view thereof.
The broken lines in the figures illustrate portions of the solar post light that form no part of the claimed design.
